Primary Examiner — T Chase Nelson*Assistant Examiner* — Jonathan J. Han(74) *Attorney, Agent, or Firm* — Kirk A. Buhler; Buhler & Associates Patenting(57) **CLAIM**

The ornamental design for a bracket for a roof rack, as shown and described.

DESCRIPTION

FIG. 1 is a top left perspective view in an environment of use of a bracket for a roof rack, showing my new design; FIG. 2 is a top plan view of the bracket for a roof rack; FIG. 3 is a bottom plan view thereof;

FIG. 4 is a right side elevation view, the left side elevation view being a mirror image thereof, and

FIG. 5 is a left sectional view taken along lines 5-5 from FIG. 2 thereof;

FIG. 6 is a rear elevation view thereof;

FIG. 7 is a front elevation view thereof; and,

FIG. 8 is a top perspective view.

The broken lines in FIGS. 1, 4 and 5 depict environmental subject matter and form no part of the claimed design.

1 Claim, 7 Drawing Sheets(56)
